UNITED STATES PATENT OFFICE.

GEORGE A. LANIER, OF PETERSBURG, VIRGINIA, ASSIGNOR OF ONE-HALF TO WILLIAM BRAVERMAN, OF RICHMOND, VIRGINIA.

ARTICLE-HOLDER.

1,020,916.

Specification of Letters Patent. Patented Mar. 19, 1912.

Application filed May 12, 1911. Serial No. 626,867.

To all whom it may concern:

Be it known that I, GEORGE A. LANIER, a citizen of the United States, residing at Petersburg, in the county of Dinwiddie and State of Virginia, have invented certain new and useful Improvements in Article-Holders; and I do hereby declare the following to be a full, clear, and exact description of the invention, such as will enable others skilled in the art to which it appertains to make and use the same.

This invention relates to improvements in article holders and, while it may be used in other relations, it is particularly designed for use as an attachment for typewriters for detachably retaining a rubber eraser and a pencil or similar articles.

For the purpose of disclosure reference is had to the accompanying drawings illustrating the invention, in which drawings like characters designate the same parts in the several views and in which:—

Figure 1 is a fragmentary perspective view of a typewriter with my attachment applied thereto. Fig. 2 is a view in front elevation of the attachment. Fig. 3 is a view in side elevation, and Fig. 4 is a stamped blank for striking up the article holder shown in the preceding figures.

1 1 designates a typewriter having the usual slot 2 through which the ribbon guide passes forming an edge 3, which cooperates with the edge 4 of the typewriter frame to hold the article holder in position as hereinafter described.

Referring to the drawing a blank is stamped out of resilient metal providing a narrow strip or fastening arm 5, having its end bent under as at 6 to form a hook end 40 gaging beneath the edge 3 and terminating in an enlarged portion adapted to be bent

downwardly to form a depending arm, which enlarged portion is slotted as at 7, providing the arms 8 and central tongue 9 which latter is bent inwardly toward the hook 6 to form a similar hook for engaging beneath the edge 4 of the typewriter frame. The arms 8 are bent upwardly, inclining slightly outwardly as at 10 thence extending inwardly as at 11 and bent over upon themselves as at 12 to form upwardly and downwardly disposed pockets 13 and 14, the walls of which are resilient and have restricted openings or neck portions 15 and 16, whereby an eraser or a pencil may be forced within said pockets through the restricted neck openings and retained therein by the resiliency of the walls of said pockets.

Having thus described a practical and preferred embodiment of the invention, the particular features of novelty will be pointed out more succinctly in the following claim.

What I claim is:—

An article holder formed from a blank of flat resilient metal comprising a fastening arm having one end turned under and at the other end an enlarged bifurcated extension bent downwardly at a right angle thereto, said extension having an intermediate short tongue bent inwardly toward the bent end of said horizontal arm, and said bifurcated extension being bent upon itself to form upwardly and downwardly opening resilient pockets, substantially as described.

In testimony whereof I affix my signature, in presence of two witnesses.

GEORGE A. LANIER.

Witnesses:
